UNITED STATES PATENT OFFICE

133,126

DESIGN FOR AN AIRPLANE

Robert J. Woods, Grand Island, N. Y., assignor to
Bell Aircraft Corporation, Buffalo, N. Y.

Application April 7, 1941, Serial No. 100,178

Term of patent 14 years

To all whom it may concern:

Be it known that I, Robert J. Woods, a citizen of the United States, residing at Grand Island, in the county of Erie and State of New York, have invented a new, original, and ornamental Design for an Airplane, of which the following is a specification, reference being had to the accompanying drawings, forming part thereof.

Fig. 1 is a top plan view of an airplane showing my novel design;

Fig. 2 is a front elevational view of the airplane of Fig. 1 with the landing gear thereof in retracted position; and

Fig. 3 is a side elevational view of the airplane of Fig. 1 with the landing gear thereof in retracted position.

I claim:

The ornamental design for an airplane, as shown.

ROBERT J. WOODS.
